UNITED STATES PATENT OFFICE

JOSEPH A. GRIMM, OF LITTLE NECK PARK, NEW YORK

DESIGN FOR A RACK FOR HOLDING CLOTHES, SHOES, JEWELRY, OR SIMILAR ARTICLES

Application filed June 14, 1932. Serial No. 44,075. Term of patent 3½ years.

To all whom it may concern:

Be it known that I, JOSEPH A. GRIMM, a citizen of the United States, residing at Little Neck Park, in the county of Nassau and State of New York, have invented a new, original, and ornamental Design for a Rack for Holding Clothes, Shoes, Jewelry, or Similar Articles, of which the following is a specification, reference being had to the accompanying drawing, forming part thereof.

In the accompanying drawing:

The figure is a perspective view of a rack for holding clothes, shoes, jewelry, or similar articles embodying my new design.

I claim:

The ornamental design for a rack for holding clothes, shoes, jewelry, or similar articles as shown.

JOSEPH A. GRIMM.
